UNITED STATES PATENT OFFICE

166,858

TUMBLER OR SIMILAR ARTICLE

Zosia Jezowski, Orange, N. J., assignor to Corning
Glass Works, Corning, N. Y., a corporation of
New York

Application September 21, 1949, Serial No. 5,119

Term of patent 7 years

(Cl. D36—8)

To all whom it may concern:

Be it known that I, Zosia Jezowski, a citizen of the United States of America, residing at Orange in the county of Essex and State of New Jersey, have invented a new, original, and ornamental Design for a Tumbler or Similar Article, of which the following is a specification, reference being had to the accompanying drawing forming a part thereof.

The sole figure is a perspective view of a tumbler or similar article, showing my new design. The design pattern is repeated at spaced intervals about the tumbler of conventional shape.

The dominant features of the design reside in the surface ornamentation as shown in heavy black on the drawing.

I claim:

The ornamental design for a tumbler or similar article, substantially as shown and described.
ZOSIA JEZOWSKI.
